HEARING DEVICE FOR THE DEAF

Filed Aug. 22, 1927

FIG. 1.

Frank E. Miller
INVENTOR

Alfred Gitter
ATTORNEY

UNITED STATES PATENT OFFICE

FRANK E. MILLER, OF NEW YORK, N. Y.

HEARING DEVICE FOR THE DEAF

Application filed August 22, 1927. Serial No. 214,513.

It is an object of my invention to provide a hearing device for the deaf which will fit snugly into the ear and at the same time have an outward protruding portion which will 5 completely cover the outer ear.

said electromagnet, an armature arm cooperatively connected with said diaphragm, an outer larger diaphragm shaped to encompass the outer ear and actuated by said armature arm, said outer diaphragm being eccentrically connected to and actuated by said armature arm, all as and for the purposes described.

In witness whereof I have signed these specifications this 15th day of August, 1927.

FRANK E. MILLER, M. D.

10 My device will be more readily understood by reference to the accompanying drawing. In the drawing, Fig. 1 is a sectional elevation of my device. E is a hollow tube portion constructed of vulcanite or other suitable material which may be inserted directly into the ear and which will form a support so that the remainder of the device itself will be sustained in the hearing position. This portion E is directly connected to the case C enclosing 15 the diaphragm D and the magnets M and M' connected with battery leads L and L'. The diaphragm D is connected through the connecting link P which may be adjustable to the outer diaphragm D' by means of a suitable screw or other fastening device X. The 20 diaphragm D' completely encloses the outer ear so that by use of the diaphragms D and D' the reproduced sounds are connected both to the eardrum, if any, through the hollow 25 passage in E, and also through the bones of the side of the face by means of the diaphragm D', so that it will be seen that I obtain the application of the reproduced sound 30 both to the inner and outer ear.

35 Having thus described my invention, what I claim and desire to secure by United States Letters Patent is:

1. In a hearing device for the deaf, a hollow tube adapted to be inserted in the human 40 ear and thereby supported, a case containing an electromagnet, a diaphragm actuated by said electromagnet, an armature arm cooperatively connected with said diaphragm, an outer larger diaphragm shaped to encompass 45 the outer ear and actuated by said armature arm, all as and for the purposes described.

2. In a hearing device for the deaf, a hollow tube adapted to be inserted in the human 50 ear and thereby supported, a case containing an electromagnet, a diaphragm actuated by
